GOLOSH OR OVERSHOE

Filed Nov. 8, 1924

2 Sheets-Sheet 2

Fig. 6.

UNITED STATES PATENT OFFICE.

MORLAND MICHOLL DESSAU, OF LONDON, ENGLAND.

GOLOSH OR OVERSHOE.

Application filed November 8, 1924. Serial No. 748,704.

To all whom it may concern:

Be it known that I, MORLAND MICHOLL DESSAU, a citizen of the United States, residing at London, England, have invented 5 a new and useful Golosh or Overshoe, of which the following is a specification.

My invention relates to an improved golosh or overshoe for wearing over footwear in wet weather and has for its object to provide a simple, light and compact device 10 adapted to be readily placed in position over the forepart of the boot or shoe so as to prevent the ingress of damp or wet through the soles or seams and so keep the wearer's feet 15 dry and warm. A further object of this invention is to construct such a golosh so that it will have a neat and artistic effect.

According to this invention, the golosh or overshoe is formed from plantation smoked 20 sheet, crêpe or other rubber which may be ribbed or plain or printed or embossed thereon. The upper is cut out to the correct form and placed round a suitable former. A sole piece of a desired shape is then secured to 25 the edges of the upper. The whole is then turned inside out and placed upon a hollow former. An insole which preferably conforms in shape to the sole piece is then secured to the edges of the upper and to the 30 sole so that the edges of the upper will be secured between the outer edges of the sole piece and the insole. The sole portion of the golosh extends up into the waist of the boot or shoe adjacent to the front of the 35 heel, and the upper extends over the instep and is shaped or pulled up to fit tightly around the boot or shoe at this point.

The blank forming the upper is preferably so shaped as to provide an integral 40 strap which extends round the heel portion of the boot or shoe so as to retain the golosh in position. Suitable openings may be formed in the upper to permit portions of the footwear or the wearer's stockings to 45 show through or these openings may if desired be covered with suitable transparent rubber. If desired, however, the rear strap may be made separately and the front ends thereof may be splayed out into a number 50 of ribbon shaped strips which are attached at their ends to the upper of the golosh, thus distributing the pull and affording a decorative effect, or they may be made double in which case the ends are left opened so 55 that they may be affixed by attaching to the surface and inner side of the upper. The

heel strap may however be entirely dispensed with in which case the golosh is made to fit tightly round the waist of the foot so that the elasticity of the rubber will retain 60 it in position. A suitable moisture excluding cushion may be provided at the rear edge of the sole. This cushion may comprise two strips secured together at their edges so as to enclose air between them and form a 65 resilient cushion. A similar cushion may also be provided in the back of the strap which engages round the heel so as to assist in retaining this in the correct position.

In order that my invention may be readily 70 understood, reference is made to the accompanying drawings, in which:—

Fig. 1 is a sectional elevation of an improved golosh for ladies' wear constructed 75 according to my invention.

Fig. 2 is an elevation partly in section of another form of golosh for ladies' wear shown in position on the foot which is indicated in dotted lines.

Fig. 3 is an elevation of a form of golosh 80 without an integral heel strap.

Fig. 4 shows the blank for forming the upper of a golosh of the type shown in Fig. 2.

Fig. 5 shows the partly formed golosh 85 comprising an upper turned inside out and secured on a former ready for attaching the insole.

Fig. 6 is a part cross section through the sole of the golosh showing the manner in 90 which the edges of the upper are secured between the sole piece and the insole, and

Fig. 7 is a section through a cushion for securing at the rear edge of the sole for the purpose of excluding moisture.

Referring to Fig. 1, a sheet of crêpe, smoked plantation or other rubber is cut to the correct form to make the upper 1 and is placed inside out over a suitable former 2 the fore part of which is hollowed out to 100 enable the edges 3 of the upper to be turned in and secured by suitable tacks or the like as shown in Fig. 5, or by plates or securing irons or grips not shown.

An insole 4 is then cut to the correct 105 shape and secured at its edges to the edges 3 of the upper. The tacks are then withdrawn and the partly formed golosh is removed from the former. It is then turned right side out and placed on a plain former. 110 A sole piece 5 is cut to the correct shape and secured to the undersurface of the go-

losh so as to adhere firmly to the insole 4 and the edges 3 of the upper 1, which are thus secured between the insole 4 and the sole piece 5. Alternatively, I may use a solid last upon which is secured a sheet of crêpe rubber or crêpe rubber lined or faced with any suitable lining material upon which the edges of the upper are secured and an outer sole affixed or I may reverse the order 10 of building up by securing the outer sole to the last and finishing with the inner lining in which latter case the completed golosh is turned inside out, so that the insole is located in the interior with its faced 15 linings. The top edge 6 of the upper is inturned to form a bead as shown in the drawing and to strengthen this edge against accidental tearing.

A heel strap 7 extends round the heel of 20 the footwear and at its two ends 8 branches out into a number of ribbon like strips 9 whose ends are secured to the upper 1 at suitable intervals around its upper edge 6. This distributes the tension upon the golosh 25 and at the same time affords a decorative appearance. On the inner face of the insole 4 and near its rear edge is provided a suitable pneumatic cushion 10 to assist in the exclusion of moisture. This pneumatic 30 cushion is constructed as shown in detail in Fig. 7, and comprises two strips or pieces 11 secured together at their edges so as to entrap a suitable quantity of air between them. This is secured inside the sole and 35 serves to exert a resilient pressure against the undersurface of the sole of the boot or shoe. A similar cushion 12 is shown arranged in the back of the heel strap 7 being secured on the inner surface thereof so as 40 to bear against the back of the boot or shoe.

Referring now to Fig. 2 this shows a somewhat different shape of golosh in which the heel strap 20 is constructed in one piece with the upper 21. A suitable blank 22 for constructing this form of golosh is shown in 45 Fig. 4. In this blank is provided an opening 23 so as to form the heel strap 20 and a further opening 24 is provided over the instep so as to permit a portion of the foot- 50 wear or the wearer's stocking to show through. The intervening portion 25 between the openings 23 and 24 thus forms a strap which extends across the wearer's instep. The openings 23 and 24 are formed 55 with a bead 26 by doubling the edges of the material so as to strengthen them and a similar bead 26 extends all round the rear edge of the blank as shown in Fig. 4. The sole 5 and the insole 4 are secured as 60 described in connection with Figs. 1, 5 and 6, and in this case the rear edge of the sole 5 is extended and turned over inside the insole at 27. A decorative piece of rubber 65 28 having a series of splayed ends 29 is secured over the strap 25 and may be of a

different colour from that of the material from which the remainder of the golosh is constructed.

In Fig. 3 a simple form of golosh is shown constructed substantially as described 70 with reference to Fig. 1 and adapted to fit over the fore part of the boot or shoe only, no strap being employed to engage round the back thereof, or straps may be added crossing over or as shown in Fig. 1 or they 75 may be made so that the straps are secured by button fasteners easily detached or secured as desired by the users. The upper 1 is secured to the sole 5 and the insole secured thereto as described with reference to 80 Figs. 1, 5 and 6, but in this case the rear edge of the sole 5 projects at 30 so as to form a tab by means of which it may be pulled into position on the footwear. A beaded edge 6 is provided round the opening 85 to the golosh similar to that of the golosh shown in Fig. 1, and this opening is made of such a size that when pulled into position on the footwear it will grip the latter tightly so as to be firmly retained in position. If desired the interior of the fore part of the golosh may be lined with silk 90 or other suitable lining material as indicated in the sectional view in Fig. 6. This lining material may extend over the whole 95 of the interior of the fore part of the golosh or over the upper or the insole only.

The rubber may be dyed any colour, or spread with latex and finely ground leather, meal, fibrous pulp blown or spread upon 100 the face of the upper, or the upper may be printed or embossed on its surface to give effects in imitation of leather, fabric or the like.

The extreme ends of the toes may be boxed 105 or strengthened to arrest the forward action of the foot wearing through the upper.

The foothold may be made on a machine in which the sole is affixed to the last and the edges folded over to grip same and 110 by rolling and pressing or pressing into a matrix containing the outer sole the two soles with the edges of the upper are firmly secured on both sides. While several forms of constructions are shown and fully 115 described, I may employ a pneumatic last made after the manner of gas bags now used in motor tyre manufacture, the operation in which case can be performed by building up either after inflation or the golosh 120 made in the flat and the gas or air bag blown to shape after being inserted into the upper of the golosh. The opening in the upper may be closed by filling with a fabric material, which has been made waterproof by 125 preference and a number of striking effects thereby obtained, or in place of the fabrics leather or celluloid may be usefully employed.

The goloshes or overshoes are finished by 130

vulcanizing by means of the "Peachey" or other suitable vulcanizing process.

I claim:-

1. A golosh or overshoe comprising an upper formed in one piece from a blank of plantation rubber crêpe, an inturned edge to said upper, an insole formed from a blank of plantation rubber crêpe secured to the inner surface of said inturned edge, an outsole formed from a blank of plantation rubber crêpe secured to the outer surface of said inturned edge and to said insole, and an opening at the rear of the overshoe out of which the rear part of the ordinary shoe ⁵ can extend, said upper having free edges all of which are formed with a reinforcing bead by doubling the edges.
- 10 2. A golosh or overshoe according to claim

1, including a rubber air cushion secured to the upper surface of the overshoe sole and ²⁰ near the rear edges thereof.

3. A golosh or overshoe adapted to fit the fore part of an ordinary shoe, comprising an upper formed from a rubber blank, an inturned edge to said upper, an insole formed from a rubber blank secured to the inner surface of said inturned edge, an outsole formed from a rubber blank secured to the outer surface of said inturned edge, and a rubber strap adapted to pass round the heel ²⁵ of the ordinary shoe, each end of said strap being divided into a number of ribbons which are secured to the upper at suitable intervals near an opening, through which the rear part of the ordinary shoe extends.

MORLAND MICHOLL DESSAU.
